UNITED STATES PATENT OFFICE

92,846

DESIGN FOR A BURNER CASING

Lurelle Guild, Darien, Conn., assignor to May Oil
Burner Corporation, Baltimore, Md., a corporation of Maryland

Application April 19, 1934, Serial No. 51,462

Term of patent 7 years

To all whom it may concern:

Be it known that I, LURELLE GUILD, a citizen of the United States, and residing in the city of Darien, in the State of Connecticut, have invented a new, original, and ornamental Design for Burner Casing, of which the following is a specification, reference being had to the accompanying drawing, forming a part thereof.

I claim:

The ornamental design for a burner casing as shown.

In testimony whereof, I affix my signature.

LURELLE GUILD.
